AQUARIUM CLEANING DEVICE

Allan H. Willinger, New Rochelle, N.Y., assignor, by
mesne assignments, to Metaframe Corporation, Haw-
thorne, Calif., a corporation of Delaware

Filed Feb. 28, 1969, Ser. No. 15,964

Term of patent 14 years

Int. Cl. D7—99

U.S. Cl. D49—25

F/G. 1.

F/G. 2.

F/G. 3.

FIG. 4.

FIG. 1 is a perspective view of an aquarium cleaning device, showing my new design;

FIG. 2 is a top view thereof;

FIG. 3 is a side view thereof; and

FIG. 4 is a back view thereof.

The characteristic features of my design reside in the configuration of a scraper in combination with a sponge stick.

I claim:

The ornamental design for an aquarium cleaning device, substantially as shown and described.
